UNITED STATES PATENT OFFICE.

WILLIAM C. SLEEMAN, OF BIRMINGHAM, ALABAMA.

RAILWAY-CAR TRUCK.

Application filed May 27, 1927. Serial No. 194,677.

This invention relates to improvements in railway car trucks and aims to provide a novel arrangement of supporting springs whereby the spring capacity is increased over 5 the present American Railway Association standards. The invention further aims to provide an arrangement of primary and secondary springs, the latter of which do not start to function until the car has been partially loaded.

In the accompanying drawings, Fig. 1 represents partial side elevation and section of a truck embodying my invention;

Fig. 2 is a plan view thereof with parts in 15 section;

Fig. 3 is a cross section on line 3—3 of Fig. 2;

Figs. 4 and 4^a show a plan and end view of 20 springs for a 40 ton capacity car;

Figs. 5 and 5^a show a similar arrangement of springs for a 50 ton capacity car;

Figs. 6 and 6^a are similar views for a 70 ton capacity car;

Fig. 7 is a plan view of a spring plank;

Fig. 8 is a side elevation of Fig. 7;

Fig. 9 is a plan view of an alternate form 25 of bottom spring plate;

Fig. 10 is a section on line 10—10 of Fig. 9;

Figs. 11 and 11^a are plan and section of a 30 spring plate;

Fig. 12 is a fragmentary cross section of an alternate arrangement showing a combination spring plank and spring retainer;

Fig. 13 is a horizontal cross section on line 35 13—13 of Fig. 12;

Fig. 14 is a partial cross section showing a modified spring arrangement; and

Fig. 15 is a horizontal cross section on line 40 15—15 of Fig. 14.

Referring to the drawings, 1 represents a 45 truck side frame having a tension member 2, compression member 3 and bolster columns 4. A spring plank 5 spans the distance between said frames and rests upon the tension members 2 between the bolster columns 4.

By means of this invention the spring capacity of the truck is increased by using more than the usual number of standard American Railway Association springs for the different 50 capacity cars. In the truck illustrated, the spring grouping of Fig. 5 is applied. The outer springs 6 are separate from the central spring group 7 and are held in place at the bottom by a boss 8 pressed upwardly in spring 55 plank 5 and by depression 9 in bolster column 4 of the side frame and recess 10 in the

bottom of bolster 11. The depression 9 in the side frame is constructed so that the top portion 12 will act as an abutment for springs 6 and prevent their displacement. The bolster 11 is applied to side frames 1 in the usual manner, the opening 13 of side frames 1 being of sufficient size to permit its assembly. Bolster guides 14 are made preferably integral with the bolster 11 and properly position the bolster and frames with respect to one another. The grouping of springs is composed of a central group 7 of four or more springs with top plates 15 and bottom plates 16 which are held in place by a bolt or bolts 17 extending from plate to plate, these plates being preferably the same shape and size as the existing 70 ton American Railway Association standard plates. The outside group of springs 6 may be either single or double coil 60 and are preferably separate from the central group 7. To apply the spring group the outside springs 6 are placed as shown in dotted lines 18 at Fig. 5 so as to clear the edge 19 of bolster column 4. After the group of springs are thus applied the outside springs 6 are forced over the boss 8 of spring plank 5 and under the portion 12 of bolster column 70 guide 4. When it is desired to omit the spring boss 8 on the spring plank 5, the bottom central spring plate 16 may be made as shown in Figs. 9 and 10, so as to form a bottom spring seat for the entire group of springs.

The spring plank 5 is made preferably 80 with flanges 20 merging into a flat plate over the side frame tension member, but if desired, flanges may be made continuous. The ends 21 of spring plank 5 are flanged upwardly and one or more projections 22 are 85 punched up from the spring plank to prevent the springs from displacement.

As an alternate means for holding springs 90 in position, the side frame 1 of Fig. 12 is provided with bosses 23 which fit holes 24 in spring plank 5 and extend sufficiently above spring plank 5 to project into springs 6, thus preventing movement of said springs 6 and at the same time properly positioning side frames 1.

In the modification shown in Fig. 14, I use the standard American Railway Association spring 25 which is partially compressed when applied to the truck and held in compression by top and bottom spring plates 26 which are 100 tied together by bolt or rivet 27. In this arrangement, the bolster is provided with 105

downwardly projecting lugs 28 which in shape are substantially concentric with the springs 25. Said lugs 28 position springs 25 and retain them in a vertical position. Clearance is provided between top of the spring plates 26 and the bottom of the bolster 11 to permit partial compression of central group of springs 7, before springs 25 begin to function. The spring plates 26 as shown in Figs. 11 and 11^a are made preferably circular in shape and formed with a central depression 30 for bolt 27. The side frame 1 is provided with holes 29 in top of the tension member 2 to permit movement of bolt 27 when springs 25 are fully compressed.

The springs 7 which normally support the truck bolster are herein termed primary springs and the other springs 6 which do not come into play until after a predetermined load has been imposed on the truck bolster are herein termed secondary springs.

Though I have described quite specifically the design and arrangement of certain car trucks illustrated, it is not to be construed that I am limited thereto since various changes in arrangement and substitution of equivalents may be made by those skilled in the art without departing from the invention as defined in the appended claims.

30 What I claim is:—

1. In a car truck, in combination, a side frame formed with a bolster opening, a bolster, a pair of springs normally out of contact with but adapted to coact with said bolster, said side frame having at least one column provided with an indented portion bridged by a substantially horizontal abutment shoulder normally engaging said springs.

2. In a car truck, a side frame formed with a bolster opening, a bolster, a spring plank

resting on said frame, a group of springs resting on spring plank, said spring plank having its entire undersurface in one horizontal plane and being formed at its extremities with upturned flanges and near each end 45 with struck-up ears adapted to engage the exterior of said springs to prevent displacement thereof.

3. In a car truck in combination, a side frame formed with columns which define a 50 bolster opening, a spring plank extending into said opening, a group of springs resting on spring plank, a truck bolster whose entire lower face lies in the same plane and which is normally supported by primary 55 springs, the remaining secondary springs of said group normally having clearance with the bolster so as to afford a partial movement thereof before coming in contact with the said secondary springs, said bolster having 60 lugs depending from its lower face adapted to engage the exterior of said secondary springs to prevent lateral displacement thereof.

4. In a car truck in combination, a side 65 frame formed with columns which define a bolster opening, a spring plank extending into said opening, a group of springs resting on spring plank, a truck bolster normally supported by primary springs, the remaining 70 secondary springs of said group normally having clearance with the bolster so as to afford a partial movement thereof before coming in contact with the said secondary springs, said columns having indented portions 75 bridged at their tops by abutments adapted to engage the secondary springs.

In witness whereof I have hereunto signed my name.

WILLIAM C. SLEEMAN.
